UNITED STATES PATENT OFFICE

160,432

MAGAZINE STAND

Omer Rubrite, Chattanooga, Tenn.

Application March 10, 1949, Serial No. 1,318

Term of patent 7 years

(Cl. D33—2)

To all whom it may concern:

Be it known that I, Omer Rubrite, a citizen of the United States, residing at Chattanooga, in the county of Hamilton and State of Tennessee, have invented a new, original, and ornamental Design for a Magazine Stand, of which the following is a specification, reference being had to the accompanying drawing, forming part thereof.

I claim:

The ornamental design for a magazine stand, as shown.

OMER RUBRITE.
